UNITED STATES PATENT OFFICE.

CLAUDE A. HERMAN, OF STRATFORD, CONNECTICUT.

DESIGN FOR A HAND PIECE FOR FLEXIBLE SHAFTS FOR FREE-HAND MILLING OPERATIONS.

Application filed October 31, 1927. Serial No. 23,952. Term of patent 7 years.

To all whom it may concern:

Be it known that I, CLAUDE A. HERMAN, a citizen of the United States, residing at Stratford, county of Fairfield, State of Connecticut, have invented a new, original, and ornamental Design for a Hand Piece for Flexible Shafts for Free-Hand Milling Operations, of which the following is a specification, reference being had to the accompanying drawing, forming part thereof.

Fig. 1 is a perspective view of a hand piece for flexible shafts for free hand milling operations, showing my new design, and Fig. 2 is a top plan view thereof.

I claim:

The ornamental design for a hand piece for flexible shafts for free hand milling operations, substantially as shown.

CLAUDE A. HERMAN.
